UNITED STATES PATENT OFFICE

BARTHOLOMEW O. CUDDIGAN, OF ANOKA, MINNESOTA, ASSIGNOR OF ONE-THIRD TO O. B. DIBBLE AND ONE-THIRD TO F. W. HERMANN, BOTH OF RED WING, MINNESOTA

VINE AND POTATO SEPARATOR AND POTATO BUNCHER

Application filed November 22, 1930. Serial No. 497,451.

My invention has for its object to provide an improved vine and potato separator and a potato buncher for potato diggers, and, to this end my invention consists in the novel 5 devices and combinations of devices herein-after described and pointed out in the claims.

The accompanying drawings illustrate my invention in its preferred form as applied to the delivery end of a potato digger; and in 10 said drawings like notations referring to like parts throughout the several views,

Fig. 1 is a plan view of my improvements as applied to a potato digger with some parts broken away;

Fig. 2 is a right side elevation of the parts shown in Fig. 1;

Fig. 3 is a detail in vertical section showing the lower end of the potato accumulator or hopper and the dropper attached thereto; and

Fig. 4 is a substantially horizontal section on the line 4—4 of Fig. 2.

As is well known, the delivery end of an ordinary standard potato digger includes a 25 trunk or body portion 5 mounted in an inclined position on the axle 6 of a two wheeled truck. At the forward end of this trunk or body 5 is located a digging shovel not shown, in the drawings. In this trunk 5 is mounted 30 a slat and link elevator 7 mounted on suitable sprockets, only the upper pair of which are shown in the drawings and numbered 8. These sprockets 8 are carried by a common shaft, one end of which appears in Fig. 2 35 of the drawings and is marked with the numeral 9. One of the truck wheels, the right hand member as shown, is provided with a spur gear 10 which engages with the gear 11 on the end of the shaft 9 and hence as the 40 truck wheels revolve, motion will be imparted to the sprocket 8 and these in turn will impart motion in the right direction to this slat and link elevator 7. The said elevator 7 receives, at its lower end, the vines. 45 the potatoes and most of the dirt excavated by the shovel of the digger, and as these materials travel upward with the said elevator most of the dirt will be shaken out and dropped to the ground, but the potatoes and 50 the vines will be carried up by the upper

running fold of said elevator 7 and be delivered over the upper end of the same.

In the potato digger illustrated, the upper end of the trunk 5 is carried rearward to a considerable distance, affording a portion thereof, which, for distinction, is marked with the reference notation 5a. In this part 5a of the trunk is mounted a second elevator 12 of the slat and link type on suitable supporting sprockets 13 fixed in pairs, respectively, to two corresponding supporting shafts, the ends of which appear in Fig. 2 of the drawings, and are marked with the numerals 14 and 15, respectively, 14 denoting the lower shaft, and 15 the upper shaft, 60 which, through the sets of sprockets 13, hitherto noted, impart traveling motion to the second elevator 12. This motion is secured through a link belt chain 16, the forward end of which engages with the sprocket 17 65 on the right end of the shaft 9 to which are fixed the sprockets 8 that impart motion to the main or primary elevator 7. The rear end of said chain 16 engages a sprocket 18 on the right end of the shaft 15 that supports the sprockets 13 that impart motion to the second elevator 12. Some of the slats of 70 said elevator 12 are shown as provided with teeth 12a.

Directly below the rear or upper end of said 75 second elevator 12 is located a cross rod 19 fixed in the trunk walls, and on this rod 19 are pivoted a series of arms 20 which extend clear to the rear end of the machine. An endless carrier 21 of the toothed slat and chain 80 type is mounted on four sprockets 22, two of which are fixed to the shaft 23, and the other two to the shaft 24. The shafts 23 and 24 are suitably mounted in the side brackets 25 fixed to the side walls of the trunk body 5a 85 and extending rearward therefrom in a horizontal position. The shaft 24 extends, at one end, outward, beyond the adjacent bracket 25 and is provided with a sprocket 26 engaged by a link belt chain 27, the forward end of 90 which is engaged by a sprocket 28 on the shaft 15, which imparts motion to the second elevator 12. This endless carrier 21 is so located and mounted that it travels in a horizontal plane and is so positioned that its 95 100

forward end is below the delivery end of the second elevator 12, in position to receive the potatoes and the vines from the delivery end of said elevator 12. The rods 20 overlie the upper running fold of the endless carrier 21, and the cross slats of this carrier are of such heights and the rods 20 are so located that the rearmost slats will raise the rear ends of the rods 20 and impart an up-and-down shaking motion thereto, said elements 20 and 21 constituting a vine and potato separator.

The carrier 21 is located at a considerably lower level than the delivery end of the second elevator 12, and hence, a series of inward turned guards 29 are applied so as to prevent the vines from moving sidewise off from the shaking arms 20. As shown, the said guards 29 are in the form of curved rods having their upper ends secured to the side walls of the portion 5a of the trunk body, and their lower ends secured to the brackets 25. The numeral 30 is a hopper-like receptacle having its upper end secured to the brackets 25, so that it is carried by said brackets with its forward edge slightly under-reaching the delivery end of the second elevator 12, and its open upper end, or mouth, located directly below the receiving end of the endless carrier 21. This hopper 30 is provided with a dropper normally closed, but releasable at the will of the driver of the machine. As shown, this dropper is made up of a solid, or door-like piece 31, hinged to the forward wall of the lower end of the hopper 30, and of a series of spring fingers 32, all of which are separately hinged to the solid portions 31, forward of the edge of said door-like part 31 and bent upon themselves so that their rearward portions extend upwardly on an incline with their tips normally resting against the rear edge of the rear wall of the hopper 30. Headed and nutted bolts 33 pass through the solid portion 31 of the dropper and through holes in each of the spring fingers 32, and these bolts are subjected to coiled springs 34 re-acting between the nuts on the bolts and the underfaces of the spring fingers, and therefore, tending to hold the spring fingers in their closed position, as shown by the full lines in Figs. 2 and 3 of the drawings. The said parts 31 and 32 afford a complete closure for the lower end of the hopper 30, so far as potatoes are concerned; and, when this closure is permitted to open, the potatoes, of course will drop out. This closure is controlled by the hereinbelow named connections. The numeral 35 represents a bell crank lever pivoted to one of the side walls of the hopper 30. The rear end of this bell crank lever 35 is connected by a link 36 to the solid part 31 of the hopper closure, at some distance away from the pivotal connection of the part 31 to the hopper 30. The forward arm of said bell crank 35 is connected by a rod 37 to a foot lever 38 pivoted to an upstanding bracket arm 39

fixed to the trunk body 5, as clearly shown in Fig. 2 of the drawings. The connection between the rod 37 and the lever 38 is a pivotal one. The location of the pivot for said lever 38 is higher than the pivot of the bell crank 35 and the throw of the lever 38 is of such extent that when the said lever is turned downward into its lowermost position, its outer end will stand below a straight line through the pivots of said two levers, or, in other words, be below the dead center and will, therefore, hold the closure of the hopper 30 in its closed position, as shown in Fig. 2 of the drawings; but when the lever 38 is thrown upward to its limit, then the said closure will drop by the gravity of its load of potatoes, although this can be assisted by the connections from the lever 38, and the accumulated bunch of potatoes will be dropped onto the ground.

As already noted, the side walls of the hopper 30 are rigidly secured to the brackets 25, the hopper being of a width to extend entirely across the machine. The upper end of the hopper 30 is open thus affording a mouth extending entirely across the machine for the reception of the potatoes from the endless carrier 21. The rods 20 which overlie the carrier 21 are spaced sufficiently far apart not to interfere with the free downward passage of the potatoes, but the said rods retain the vines. The slats on the endless carrier 21 are also so far apart that they do not interfere with the passage of the potatoes into the mouth of the hopper.

The operation of the machine as an entirety may be summarized as follows:

The potatoes, vines, and dirt, excavated by the shovel (not shown) of the digger are received on the primary elevator 7 and carried upward thereby, and, while this is being done, most of the dirt will drop through between the slats or cross rods of the elevator 7 to the ground. The vines and the potatoes will be carried on upward to the end of the travel of said main elevator 7 and will be delivered therefrom onto the receiving end of the second elevator 12, and while traveling with the same, the rest of the dirt will be dropped out. From the upper end of the elevator 12, the potatoes and vines will be delivered together onto the rods 20 and the potatoes will fall through onto the carrier 21, while the vines will be held by the rods 20 and moved rearward by the teeth on the slats of said carrier 21 and be thrown off from the tail of the machine onto the ground. The potatoes drop down between the rods 20 and the slats of the carrier 21 into the hopper 30. The potatoes will accumulate in this hopper to whatever extent may be desired by the driver of the machine, and then he will manipulate the lever 38 so as to throw it upward and rearward beyond its dead center and the closure of the hopper will immediately open under

the weight of its bunch of potatoes supported thereby and drop to the ground, allowing the potatoes to drop out in a bunch. Thereupon, the driver will again manipulate the lever 38 5 so as to throw the same forward and downward into its dead center position and bring the closure back to its closed position. This dropping action is so quickly effected that practically no potatoes will drop through the 10 lower end of the hopper 30 while the closure is open, except the accumulated bunch, or, at least, if any potatoes do happen to drop they will fall onto the bunch of potatoes already 15 lying on the ground while the machine moves forward beyond the bunch. The gravity of the bunch of potatoes is sufficient to open the closure when the hand lever 38 is thrown upward and backward beyond its dead center, but the driver may assist the dropping action, 20 if he so desires, by the force which he applies to said lever through the rod 37, bell crank 35, and link 36.

The fact that the spring fingers 32 are pivoted to the solid part 31 of the hopper closure and subject to the springs 34 tending to hold the fingers in their uppermost position, is a feature of advantage both in the potato dropping action and in the closing action of the closure. When the closure is in its 30 lowermost position, these spring fingers 32 will ride on the ground and the dirt coming through between the fingers, under the forward travel of the machine, will clean the fingers and help to roll the potatoes off from the 35 closure. Then, if it should happen that any of the potatoes should be caught between the fingers 32, or be speared on one or more thereof, the fingers will yield downward and outward against the springs 34 when the closure 40 is being brought to closed position by the driver's manipulation of the lever 38.

By extensive commercial usage, the efficiency of this improved machine has been demonstrated. All the parts thereof work 45 with complete success for the purposes intended.

It will, of course, be understood, that more or less of the details of the mechanism and the forms and proportions of the parts may be 50 varied without departing from the spirit of the invention herein disclosed and claimed.

It is obvious that if the potato buncher were removed from the machine illustrated in the drawings and above described, the remaining 55 elements would afford an efficient vine and potato separator, for cooperation with the elements of an ordinary standard potato digger.

It is the addition of the buncher, however, 60 which constitutes my most radical improvement in this class of machines.

While I have shown my improvements supported on the extended frame of a potato digger, it must be understood that said improvement 65 could be mounted on an independent

truck, or other movable support adapted to be coupled to any potato digger of the standard type.

What is claimed is:

1. The combination with a potato digger, 70 of vine and potato separating elements, and a potato buncher comprising a hopper adapted to receive the potatoes from said separating elements and provided with a closure upon which the potatoes accumulate when the closure is in its closed position but which closure is releasable, at the will of the driver, for dropping the bunches of potatoes, and which closure has spring fingers at its delivery edge for striking the ground when the closure is in its open position and the ends of which fingers will yield if potatoes be speared thereon or be caught between the fingers when bringing the closure into its closed position. 75

2. The combination with a potato digger, 80 of a vine and potato separator comprising an endless carrier of the toothed slat and chain type, and a series of pivoted rods overlying said carrier and receiving therefrom an up-and-down shaking motion, which separator receives the potatoes and vines from the digger, permits the potatoes to fall therethrough, and retains the vines on said rods subject to the teeth of said carrier for conducting the same off the machine. 85

3. The combination with a vine and potato separator, comprising an endless carrier of the toothed slat and chain type, and a series 90 of pivoted rods overlying said carrier and receiving therefrom an up-and-down shaking motion, of a potato buncher comprising a hopper for receiving the potatoes from said separator, a closure for the lower end of said hopper upon which the potatoes accumulate 95 when the closure is in closed position and which closure is releasable at the will of the driver of the machine for dropping the bunches of potatoes to the ground. 100

In testimony whereof I affix my signature. 110
BARTHOLOMEW O. CUDDIGAN.
